US0D1096863S

(12) **United States Design Patent** (10) **Patent No.:** **US D1,096,863 S**
(45) **Date of Patent:** **** Oct. 7, 2025**

(54) **RECEIVER FOR BOTTLING MACHINE**

(71) Applicant: **M&M Machinery Services, Inc.**, Fort Worth, TX (US)

(72) Inventor: **Alton W. Mowdy**, Fort Worth, TX (US)

(73) Assignee: **M&M Machinery Services, Inc.**, Fort Worth, TX (US)

(**) Term: **15 Years**

(21) Appl. No.: **29/977,105**

(22) Filed: **Dec. 5, 2024**

Related U.S. Application Data

(62) Division of application No. 29/851,486, filed on Aug. 29, 2022, now Pat. No. Des. 1,059,427, which is a division of application No. 29/795,581, filed on Jun. 18, 2021, now Pat. No. Des. 965,652, which is a division of application No. 29/680,459, filed on Feb. 15, 2019, now Pat. No. Des. 924,284, which is a division of application No. 29/597,122, filed on Mar. 14, 2017, now Pat. No. Des. 846,608.

(57) **CLAIM**

The ornamental design for a receiver for bottling machine as shown and described.

DESCRIPTION

FIG. 1 is a bottom perspective view of a receiver for a bottling machine in accordance with my new design.

FIG. 2 is a top perspective view thereof.

FIG. 3 is a front elevation view thereof.

FIG. 4 is a left side elevation view thereof.

FIG. 5 is a right side top view thereof.

FIG. 6 is a top view thereof; and,

FIG. 7 is a bottom view thereof.

The broken lines in the drawings depict portions of the receiver for a bottling machine which form no part of the claimed design.

1 Claim, 5 Drawing Sheets
